UNITED STATES PATENT OFFICE

LOUIS A. GEBHARD, OF WASHINGTON, DISTRICT OF COLUMBIA, ASSIGNOR TO WIRED RADIO, INC., OF NEW YORK, N. Y., A CORPORATION OF DELAWARE

INDUCTANCE SYSTEM

Application filed December 23, 1929. Serial No. 416,158.

My invention relates broadly to high frequency inductance systems and more particularly to a construction of coupling inductance for high frequency signal transmission systems.

One of the objects of my invention is to provide a mechanical system for adjusting the effective number of turns of inductance in a signal transmission circuit and controlling the coupling of the transmission circuit with respect to the radiation system.

Another object of my invention is to provide a construction of inductance system which may be readily adjusted to predetermined positions for fixing the effective inductance in the transmission circuit and the coupling of the transmission circuit with respect to the radiation system.

A further object of my invention is to provide a construction of adjustable inductance system by which a maximum value of inductance may be connected in the transmitter circuit and the coupling varied with respect to the radiation circuit by mechanical means variable with respect to each other along the inductance in such manner that the effective inductance may be varied throughout the entire length thereof for tuning the transmitter circuit while a minor portion of the inductance may be effectively selected for connection in the radiation circuit for varying the coupling between the transmission circuit and the radiation circuit.

Still another object of my invention resides in the construction of a variable inductance system having means for predetermining the position of a pair of variable contactors along a helical inductance and selectively setting the contactors in desired positions for fixing the frequency and coupling adjustment of a signal transmission system.

A still further object of my invention is to provide a construction of fluid cooled high frequency inductance system having means for variably including an effective number of turns of inductance in the transmitter circuit and a smaller number of turns in a coupling circuit for coupling to a radiation system while maintaining all of the turns of the

inductance at a predetermined temperature by means of a fluid circulation system.

Other and further objects of my invention reside in the construction of high frequency inductance system set forth more fully in the specification hereinafter following by reference to the accompanying drawings, in which:

Figure 1 shows a lateral cross-sectional view taken through a transmitter panel and illustrating the arrangement of high frequency inductance system of my invention with parts thereof shown partially in cross-section and partially in elevation; Fig. 2 shows a side elevation of the inductance system of my invention; Fig. 3 is a rear view of the inductance system looking in the direction of arrow A in Figure 1; Fig. 4 is an enlarged cross-sectional view taken through one turn of the inductance adjacent one end thereof and showing the cooling fluid connection thereto; Fig. 5 is a cross-sectional view taken through the end support of the rotatable adjusting means for controlling the effective number of turns of the inductance in the transmitter circuit and the coupling of the transmitter circuit with respect to the radiation circuit; and Fig. 6 is a diagrammatic view showing the wiring arrangement of the transmitter circuit and radiation system embodying the principles of my invention.

In high frequency transmission systems employing screen grid tubes, it is desirable to have the output circuit contain as much inductance as possible at the particular frequency of operation. This is particularly desirable for efficient operation at high frequencies and may be accomplished by having the inductance coil in the electron tube system at the transmitter arranged so that the effective inductance is continuously variable throughout the length thereof by means of a slider which passes over all of the turns of the coil. It is also desirable to provide another adjustable slider on the inductance to effect a continuously variable coupling or other adjustment. The coupling adjustment slider may be located at a point along the inductance which provides a lower effective in-

ductance than is required by the slider which is used for the tuning adjustment. This arrangement permits a system to be employed in which the sliders do not pass each other but where the sliders may be progressively changed in position throughout the length of the inductance. The inductance system of a high frequency transmitter should be maintained at constant temperature for securing maximum efficiency in operation, and the frequency change and variable coupling system of my invention is designed to permit change in the effective inductance and effective coupling between the transmitter circuit and radiation system while maintaining the inductance elements at constant temperature.

Referring to the drawings in more detail, reference character 1 designates the inductance coil which is in the form of a flat tubular member having the turns thereof located substantially in vertical planes and supported in helical formation by means of insulated laterally extending spacer members 2 which are supported at opposite ends by means of end plates 3 and 4. Screws 5 pass through end plates 3 and 4 securing the inductance in position with respect to the insulated frame. The end plate 4 has a bearing plate 6 secured adjacent the center thereof in which rotatable shaft 7 is journaled for rotary movement. The shaft 7 is in the form of a hollow conductive tube which encloses the screw 8 which is secured to the insulating member 9. The slider 10 is actuated by the rotation of shaft 7 under control of crank 14. The shaft 7 contains a longitudinally extending slot 7a through which screw 11 carried in slider 10 projects. The inner end of screw 11 engages the screw threads in the screw 8 which threads are cut to correspond to the pitch of the turns of the inductance coil 1. The rotation of shaft 7 causes turning of slider 10 which moves along the coil 1 in accordance with the position of the turns. The slider 10 carries brush members 12 which engage opposite sides of the turns of flattened tubular inductance 1. In order to impart rotative movement to shaft 7, I provide the crank 14 operative from the front of the control panel 17, which crank is insulated from shaft 7 by means of insulating member 13. Rotative movement of the crank 14 imparts corresponding movement to the beveled gears 15 operating a counter 16 which is visible from the front of the control panel 17 of the transmitter thereby permitting resetting of the slider to any selected point along the coil. The counter 16 is mounted upon plate 17a which is supported by insulating members 18 from the end plate 4. A second slider 19 constituted by brushes engaging opposite sides of the turns of flattened tubular inductance 1 is arranged to control the coupling between the transmitter circuit and the associated radiating circuit. Slider 19 is

mounted on rod 20 which slides longitudinally into tube 21. In order to prevent loss motion or displacement of the rod 20, the tube 21 is made square in cross-section to receive the rod 20 which is square in cross-section. The tube 21 is secured to arm 22 which is connected with beveled gear 23 as shown more clearly in Fig. 5. A brace 24 extends between one end of arm 22 and the extremity of the tube 21 thereby rigidly strengthening the movable assembly. The arm 22, brace 24 and gear 23 are secured together by means of pins 25 or the parts may be sweated or otherwise connected for forming an assembly rotatable in unison. The assembled group of parts 22, 23 and 24 are arranged to revolve about shaft 26 which is rigidly secured in support 27 by means of pin 28. The support 27 is carried by the insulating members 41 and 42 which are supported from the base 40 by a suitable bracket or other means. In order to impart movement to gear 23, arm 22 and brace 24, I provide resilient washer members 29 and 30 which serve as spacer means on each side of the assembled sets of parts 23, 22 and 24, permitting easy turning of gear 23 under control of gear 31 actuated by rotative movement of the beveled gears 35 through shaft 32 and insulating connecting member 34 which interconnects the gear system 35 with the gear system 31-23. The insulating member 9 which is fixed to the threaded rod 8 is connected by screw threaded portion 30a of shaft 26 with the rigid shaft 26 so that central rod 8 is maintained stationary while the hollow tubular shaft 7 revolves over the screw threaded rod 8 as an envelope. In order to insure a tight connection between insulated rod 9 and shaft 26, I apply a suitable locking cement for binding the screw threads 30a of the insertable shaft 26 with respect to the socket portion of insulating member 9. The shaft 32 which interconnects beveled gears 35 and 31 is journaled at one end in bracket 33 and at the other end in bracket 43. The beveled gear 35 is intermeshed with a correspondingly positioned beveled gear which is operated by shaft 36 and crank 37 from the front of the panel 17. The beveled gears 38 which are operated in accordance with the rotation of shaft 36 under control of crank 37 connect with the counter 39 and enable readings to be taken from the front of panel 17 for predetermining the position of the slider 19 with respect to the inductance 1. The counter 39 is mounted upon the plate 17a in a manner similar to counter 16. The end plate 3 is apertured adjacent its center as shown in Fig. 3 to permit the revolving of the parts 21, 22 and 24 through 360 degrees or some multiple thereof for moving the slider 19 over predetermined limits along the turns of the inductance 1. Connection is made to the slider 12 through binding post 44 on insulating end plate 4 which connects through bearing plate 6, the

bushing 6a associated therewith, and collar 45 with the hollow tubular shaft 7. The connection to the slider 12 is completed through the split brush 46 which engages the surface 5 of the hollow tubular shaft 7, through slider 10, flexible spring 47, and to the parts of slider 12 which wipes opposite sides of each of the turns of the flat tubular inductance 1. The connection to brush 19 is made through 10 binding post 48, bearing block 27, shaft 26, arm 22, tubular member 21, brush device 49, and rod 20. The brush 49 maintains a frictional grip upon rod 20 as the rod is adjusted with respect to the tubular supporting member 21. The resilient washer members 29 and 30 are of the disc shaped spring type having radial slots to provide a good connection between the bearing support 27 and the revolving group of parts 23, 22 and 24.

20 The inductance system is maintained in permanent position and cooling fluid supplied to the hollow tubular inductance as illustrated. The inductance 1 has flattened side walls 50 providing a narrow fluid circulating 25 path indicated at 52. The flattened tube is wound edgewise with respect to the laterally extending frame member 2. The cooling fluid enters one end of the coil, passes through the coil, and discharges from the other end thereof. The fluid connection for the entrance and discharge of the fluid is shown more clearly in Fig. 4. The exterior of the tubular inductance member is indicated at 51 and the hollow interior thereof shown at 52 with the end 30 plugged as indicated at 53 which prevents the cooling fluid from flowing out of the end of the tube. Into the side or edge of the tubular conductor 51, I provide the tube 54 which is sweated therein to provide communication 35 with the interior fluid passage 52. Over the tube 54 there is placed an insulating tubing 55 which serves to complete the path for the cooling fluid to or from the inductance per se, and at the same time serves to insulate the ends of 40 the inductance from the remainder of the cooling fluid circuit. Clamps 56 are provided to hold the insulating tubing 55 on to the tubing 54. By this construction the inductance is formed of a relatively flat tubular envelope 45 closed at each end and into the sides of the envelope adjacent each end thereof, there is admitted or delivered therefrom a suitable 50 cooling fluid.

Figure 6 diagrammatically illustrates the 55 connection of the inductance system of my invention between the output circuit of a screen grid power amplifier circuit and a radiation system. The last stage of power amplification is shown as including a screen grid tube 60 in the output circuit of which the fluid cooled inductance system 1 is connected. The slider 12 connects to the plate electrode of the electron tube system and one end of the inductance connects to the other end 60 of the output system of electron tube 60.

Proper tuning capacity indicated at 57 may be introduced across a selected number of turns of inductance by means of switch 58. The radiation system is shown as including an antenna 61 and ground 62 in series with tuning inductance 63. The slider 19 connects through condenser 64 with the radiation circuit and by adjustment of slider 19 along inductance 1 the coupling between the output system of electron tube 60 and the radiation circuit may be changed.

The slider 12 is adjustable substantially throughout the length of the inductance system, while slider 19 has a smaller variable movement with respect to the inductance system. It is unnecessary for the sliders to pass each other so that selected movement of the sliders in different proportions may be made for selectively adjusting the tuning of the circuit and the coupling of the transmitter 85 circuit with respect to the radiation system.

The frequency control apparatus of my invention is constructed for securing maximum efficiency in high frequency signal transmission, and while I have described a certain preferred embodiment of my invention, I desire that it be understood that modifications may be made and that no limitations are intended other than those imposed by the scope of the appended claims.

What I claim as new and desire to secure by Letters Patent is as follows:

1. A high frequency inductance system comprising an insulated frame structure, a fluid cooled inductance spirally positioned within said insulated frame structure, a central shaft extending through said frame structure, said shaft being divided into two conductive portions insulated from each other, a pair of brush contact members concentrically related to said central shaft and respectively supported by portions of said shaft which are insulated from each other and independent means for adjusting said brush contact members along said inductance from opposite ends thereof toward the center.

2. In a high frequency inductance system, an insulated frame structure, an inductance spirally positioned within said insulated frame structure, a central shaft extending through said frame structure, said shaft being divided into two conductive portions insulated one from the other, a brush engaging the turns of said inductance and operative under control of rotary movement of said central shaft, an independent brush engageable with the turns of said inductance, said brushes being respectively supported by portions of said shaft which are insulated from each other, and means for advancing said independent brush along said inductance from the end thereof toward the center, said means operating independently of the rotary movement of said shaft.

3. In a high frequency inductance system,

an insulated frame structure, a spirally positioned fluid cooled inductance mounted within said frame structure, a shaft member extending through said frame structure, said shaft member being divided into a pair of separate portions insulated one from the other, a contact device engaging the turns of said inductance and shiftable under control of said shaft member, an independent contact device engageable with said inductance, said contact devices being respectively rotatably supported by portions of said shaft which are insulated from each other, and separate controls for imparting independent movement to each of said contact devices.

4. In a high frequency inductance system comprising an insulated frame structure, a fluid cooled inductance spirally positioned within said insulated frame structure, a central shaft extending through said inductance, means dividing said shaft into a plurality of portions insulated one from the other, a brush contact device engaging the turns of said inductance and shiftable in position with respect thereto under control of one portion of said shaft, an independent brush contact device centered with respect to the other portion of said shaft, and means for driving said independent brush contact device around said shaft for engaging the turns of said inductance independently of the rotation of said shaft and independently of the movement of said first mentioned brush contact device.

5. In a high frequency inductance system, an insulated frame structure, a fluid cooled inductance spirally mounted within said insulated frame structure, a rotary shaft journaled centrally with respect to said insulated frame structure, said shaft being divided into two portions with an insulating connector therebetween, a contact device engageable with the turns of said inductance and adapted to be rotated around one portion of said shaft, a separate contact device engaging the turns of said inductance and controllable by the rotative movement of the other portion of said shaft, and means for independently imparting rotation to said first mentioned contact device and to said rotary shaft for advancing said contact devices along said inductance toward the center from opposite ends thereof.

6. In a high frequency inductance system, an insulated frame structure, a fluid cooled inductance spirally mounted within said frame structure, a shaft member extending centrally through said inductance, said shaft member including an insulating connector dividing said shaft member into two independent portions, a brush contact device engageable with the turns of said inductance and shiftable along said inductance in accordance with the rotation of said shaft, an independent brush contact device arranged to engage the turns of said inductance, a carrier

concentrically positioned with respect to the other portion of said shaft and having slideable connection with said independent brush contact device, and means for imparting rotary movement to said carrier independently of the rotary movement of said shaft for adjusting each of said contact devices along said inductance.

7. A high frequency inductance system comprising an insulated frame structure, an inductance spirally positioned within said insulated frame structure, a rotary shaft extending through said inductance, said shaft being divided into a pair of independent portions insulated one from the other, a contact device engaging the turns of said inductance and controllable in position along said inductance by the rotatable adjustment of one portion of said shaft, a separate contact device engageable with the turns of said inductance, a rotatable carrier concentrically positioned with respect to the other portion of said shaft, slideable connecting means interposed between said carrier and said separate contact device, and means for imparting rotary movement to said carrier independently of the rotary movement imparted to said shaft for effecting an adjustment of each of said contact devices along said inductance.

8. In a high frequency inductance system, a helical tubular inductance member, a shaft disposed in the axis of said helical member, said shaft being divided into two portions insulated from each other, a contact member engaging the turns of said inductance member, means for moving said contact member along said inductance member under control of one portion of said shaft, an independent contact member engaging the turns of said inductance member, means for moving said independent contact member along said inductance member under the control of the other portion of said shaft, a fluid inlet member attached to said tubular inductance member at one end thereof and communicating with the interior thereof, and a fluid outlet member attached to said tubular inductance member at the opposite end thereof and communicating with the interior thereof, whereby cooling fluid is delivered to one end of said tubular inductance member and flows through the entire length of said member to the opposite end thereof.

9. In a high frequency inductance system, a helical tubular inductance member, a shaft disposed in the axis of said helical member, said shaft being divided into two portions insulated from each other, a contact member engaging the turns of said inductance member, worm screw means for moving said contact member along said inductance member under control of one portion of said shaft, an independent contact member engaging the turns of said inductance member, means for moving said independent

- contact member along said inductance member under the control of the other portion of said shaft, a fluid inlet member attached to said tubular inductance member at one end 5 thereof and communicating with the interior thereof, and a fluid outlet member attached to said tubular inductance member at the opposite end thereof and communicating with the interior thereof, whereby cooling fluid is delivered to one end of said tubular inductance member and flows through the entire length 10 of said member to the opposite end thereof.
10. In a high frequency inductance system, a helical tubular inductance member, a 15 shaft disposed in the axis of said helical member, said shaft being divided into two portions insulated from each other, a contact member engaging the turns of said inductance member, means for moving said contact member along substantially the entire length 20 of said inductance member under control of one portion of said shaft, an independent contact member engaging the turns of said inductance member, means for moving said independent contact member along said inductance member under the control of the other portion of said shaft, a fluid inlet member 25 attached to said tubular inductance member at one end thereof and communicating with the interior thereof, and a fluid outlet member attached to said tubular inductance member at the opposite end thereof and communicating 30 with the interior thereof, whereby cooling fluid is delivered to one end of said tubular inductance member and flows through the entire length of said member to the opposite end thereof. 35
